MANUAL LUBRICATOR FOR IGNITION
INTERRUPTERS

Frank S. Coe and Robert H. Gibson, Springfield, Mass., assignors to American Bosch Corporation, Springfield, Mass., a corporation of New York

Application February 10, 1942, Serial No. 420,172

10 Claims. (Cl. 184—102)

The present invention relates to manual lubricators for ignition interrupters for intermittently depositing at will a small amount of oil or other lubricant on the interrupter mechanism, such as the lever, cam or cam follower thereof, of an ignition generator such as a magneto or battery ignition distributor, when the generator is at rest, and more particularly it relates to an automatic return type of lubricator for this purpose.

Heretofore, as disclosed in U. S. Patent 2,265,047, this type of lubricator mounted on the cylindrical wall of the interrupter housing is operable by a simple or unimpeded push stroke for depositing oil on the rotatable cam by contact therewith of an oil saturated wick. In some cases, this positioning of the lubricator is difficult without rearranging some of the parts of the interrupter mechanism or other parts associated therewith in the interrupter compartment within the interrupter housing, and also does not readily permit the removal or the accurate replacement of the lubricator. Furthermore, the simple push stroke to deposit oil on the cam often led to overoiling in each application or upon too frequent application by inadvertence, which resulted in pitting and burning of the interrupter contacts and sometimes in other troubles that reduced the subsequent effectiveness of the generator and thereby decreased its operating life.

One of the objects of this invention is to provide a lubricator of this general type which, instead of a simple push movement for effecting lubrication, has a turning movement throughout the entire stroke or only during a part thereof, so as either to sweep the cam or other part of the interrupter mechanism for lubricating it more effectively and with better control of the quantity deposited, or else to introduce a compound movement including pushing and turning in either sequence to at least reduce if not prevent inadvertent actuations at undesired times, or to both improve the effectiveness of lubrication and restrain undesirable applications as might result in over lubrication.

Another object, irrespective of the compound movement, is the provision for mounting the lubricator in the cap of the interrupter housing to thereby permit ready removal of the lubricator for inspection, adjustment, repair or renewals, and more accurate replacement of it thereafter, and also to thereby provide in some cases for the better accommodation of the lubricator in the interrupter compartment.

Another object is to provide lubricators which are simple, compact, durable and inexpensive, and generally of such construction as result in continued effectiveness throughout long periods of service in depositing on the interrupter mechanism a small and substantially like quantity of lubricant during each application thereof.

Still another object of the invention is to provide unitary lubricators which are of the above noted kinds and have the above noted advantages, and which are intended as replacement units and for installation on ignition generators not originally equipped therewith.

Other objects and advantages will be apparent from the following description of several embodiments within the invention, showing as examples spring-return oil lubricators arranged to contact at will the rotatable cams of aviation magnetos, taken in conjunction with the accompanying drawings showing the lubricators in normal or inoperative position. In these drawings,

Figs. 1-5 show one embodiment of the lubricator, of the turn-push type, mounted in the wall of the interrupter housing. Fig. 1 is a plan view, partly in section, of the interrupter mechanism and the lubricator; parts of the associated magneto and interrupter housing being broken away; Fig. 2 is an enlarged section of the lubricator on the line 2—2 of Fig. 1, with some parts in elevation; Fig. 3 is a section on line 3—3 of Fig. 2, with some parts in elevation; and Figs. 4 and 5 are, respectively, a sectional view of a part of the bushing of the lubricator, and an end view thereof, to illustrate the slots for guiding the plunger in its compound movements into contact with the cam and back to normal position.

Figs. 6-10 show another embodiment of the lubricator of the pushturn type, mounted in the cap of the interrupter housing. Fig. 6 shows the lubricator in side view, partly in section and partly in elevation; Fig. 7 is an enlarged section on line 7—7 of Fig. 6 with certain parts in elevation; Fig. 8 is a section on line 8—8 of Fig. 7; Fig. 9 is a development of the guiding slots in the bushing; and Fig. 10 illustrates the movement of the wick in the swinging movement to lubricate the cam.

Fig. 11 shows a longitudinal section of a third embodiment of the lubricator of the turn type, mounted in the cap of the interrupter housing; and Fig. 12 is similar to Fig. 10 but illustrating the lubricator of Fig. 11.

Referring first to the turn-push embodiment

of Figs. 1-5, the magneto 1 has an interrupter housing comprising a generally-cylindrical side wall 2 and a removable end cap 3, the wall and cap forming with the interrupter plate 4 an interrupter compartment in which are arranged in the well known way two interrupters 5 and their associated parts of well known kind. Each interrupter has cooperative contacts 6 periodically separable by the lobed cam 7 and the spring-pressed cam follower 8, and each interrupter is associated with a terminal 9, a condenser 10, and electrical conducting leads as 11 and 12.

In this embodiment, the manual lubricator, generally indicated by 13, has a bushing 14 which is screwed into the side wall 2 against a lock washer 15 to form supporting means for the lubricator in the housing, the knurled operating knob 16 being arranged to turn and slide on the smooth exterior surface of the bushing extension 17. The plunger of the lubricator has a solid cylindrical shank 18 fastened by the cross pin 19 to the cylindrical shaft extension 20 which in turn is fastened by set screw 21 to the knob and which is arranged to turn and slide against the smooth interior wall of the bushing extension 17. The plunger has at its other end a hollow portion 22 which holds an oil-saturated felt wick 23 projecting outwardly thereof as shown from an oil reservoir 24. The bushing extension 17 has two diametrically-opposite longitudinal slots 25 terminating between a low end wall 26 and a high end wall 27 about 90° each in extent. The helical spring 28 lies loosely around the plunger shank 18 and the interior wall of the bushing extension 17, with its ends 29 and 30 extending into drill holes in the bushing 14 and the shaft extension 20. With the parts in normal position as shown in Fig. 2, the spring 28 is initially tensioned and compressed, so that the ends of the cross pin 19 are spring-pressed against the sides of the high wall 27 at the end surfaces of the low walls 26.

To apply oil to the cam 7 in this embodiment of Figs. 1-5, the knob or handle 16 is turned about 90° to further wind the spring 28, and to bring the ends of the pin 19 into registry with the slots 25, whereupon the handle is pushed against the added longitudinal stress of the spring until the wick 23 contacts the registering lobe of cam 7. Upon release of the handle 16, the spring 28 first returns the plunger longitudinally and then turns it together with the shaft extension 20 and handle 16 until the parts are restored to normal position illustrated, ready for the next application.

In the embodiment of Figs. 6-10, a push-turn type of manual lubricator, generally indicated by 31, is mounted in the interrupter cap 3 at one side of the ventilator 32 therein, for lubricating the cam 1. The bushing 33 is screwed in an opening in the cap and is held against turning therein by the set pin 34. The nut 35 is screwed against the lock washer 36 on the hollow cylindrical extension 37 of the bushing to hold the cap securely between the bushing and nut. Thus the bushing 33 and the nut 35 together form supporting means fastening the lubricator to the interrupter housing so as to support it therefrom. The plunger, having the solid shank 38 and the wick holder 39, is fastened by the cross pin 40 to the shaft extension 41 which is fastened by set screw 42 to the operating handle 43. Thus the shaft extension 41 is adapted to slide and turn in the smooth interior surface of the hollow extension of the cylindrical nut

35, while the handle 43 is adapted to slide and turn on the smooth extension surface of the nut extension 44. The helical spring 45 has its ends 46 and 47 extending into drill holes in the shaft extension 41 and the bushing 33 and is initially tensioned and compressed so as to reliably hold the plunger in the normal or inoperative position shown, and to return it to that position upon being released after each application of lubricant. To guide the plunger in its compound movement of push and turn in the manually-operated lubricating stroke, and in the reverse sequence in the return spring stroke, the bushing extension 37 has near its outer end the diametrically-opposite longitudinal slots 48 and the connecting circumferential slots 49 of about 45° extent. The ends of the pin 40 are normally in registry with the slots 48 and in being pushed downwardly therein against the added compression of the spring 45, and then in being turned in the slots 49 against the added torsion of the spring, the plunger 38 is given a like compound movement in its lubricating stroke, and upon release is returned to normal position by the stressed spring in reverse sequence. The wick holder 39, retaining the wick 50, has a spun-over lip at 51 securing in place the disc 52 which has its ends 53 bent inwardly to form a lubricant-applying wick portion 54.

To apply oil to the cam 7 with this embodiment of Figs. 6-10, the handle 43 is pushed down to bring the wick 50 in the plane of the cam 7, and is then turned to wipe the wick portion 54 across the bottom lobe of the cam. Upon release, the spring 45 returns the plunger to its normal position by first turning the pin 40 back in the circumferential slots 49 and then pushing the pin through the longitudinal slots 48.

In the turn type of the embodiment of Figs. 11 and 12, the lubricator is likewise mounted in the interrupter cap 3 but with the lubricating wick 55 permanently in the plane of the cam 7. Similar to arrangement of the first or turn-push embodiment, the plunger 56 has an oil reservoir 57 and a stop formed by a shoulder between the plunger and the bushing 58. The pin 59 is arranged to be turned manually about 45° in the diametrically-opposite circumferential slots 60 of the bushing and to be returned in the reverse direction to the normal position illustrated by the then stressed spring 61 upon release of the handle 62. As in the embodiment in Figs. 6-10, the bushing 58, together with its cylindrical extension, and the nut screwed onto the cylindrical extension, form supporting means for fastening the lubricator to the housing 3 and supporting it therefrom. The operation of applying oil to the cam 7 by turning the wick portion 63 will be obvious.

It will be observed that in the turn-push type of lubricator herein disclosed, the oil or other lubricant is deposited on the cam by pushing the end of the wick to the position shown in broken lines in Fig. 1, thereby squeezing oil out of the wick onto the cam. Although the quantity deposited during each application may be small, there is a greater percentage of variation of the deposit, depending upon the pushing force exerted and the dryness of the end of the wick, than in the push-turn and the turn types which, as a result of the turn movement solely in depositing the oil, in each direction of sweep, exert a substantially constant pressure between the wick and cam. In Fig. 6, the broken line 75 shows the position of the wick during the turning

part of the movement, and in Figs. 10 and 12 the positions of the wick are shown at the beginning and end of the oil depositing strokes thereof.

It will also be observed that in connection with the turn-push and push-turn types, there is a compound manual movement required in the application of the lubricant, precluding, as a practical matter, such inadvertent or unknowing applications as have been found to lead to undesirable over-oiling resulting in pitting and burning of the interrupter contacts and therefore premature failure of the ignition generator. Furthermore, it will be observed that the low wall 28 and the longitudinal slot 25 of the embodiment of Figs. 1-5, and the slots 48 and 49 of the embodiment of Figs. 6-10, form compound guiding surfaces for the cross pins 19 and 48, with an intermediate stop between the two directional parts of the compound movement to render still more unlikely the over-oiling of the interrupter mechanism as a result of inadvertent operation of the lubricator. Likewise the end of the cylindrical extension of the bushing 53 forms a guiding surface for the cross pin 59 of the embodiment of Figs. 11 and 12.

Also it will be observed from Fig. 1, that the sometimes crowded condition of the interrupter compartment makes it impossible or undesirable to mount the lubricator in the side wall of the interrupter housing. In such and other cases, it may become desirable to mount the lubricator in the end cap as disclosed in connection with the push-turn and turn types hereof. Furthermore, by this mounting the lubricators may be readily removed with the cap without disassembly therefrom, and the lubricator then inspected, adjusted or repaired, may be readily replaced without disturbing the accurate position of the lubricator relatively to the cam.

Furthermore, it will be observed that the oil or other lubricant may be deposited on parts of the interrupter other than the cam, provided that thereafter the lubricant gets onto the cam to prevent excessive friction between it and the cam follower or followers without reaching the contacts. For instance, if the oil is deposited on the lever carrying the cam follower, it gradually flows or passes by capillary action onto the cam. Lubricant other than oil may be used, as for instance graphite, in which case the lubricant applicator may take the form of a stick or rod or otherwise, instead of the wicks as shown. Also it is possible that the interrupter mechanism may be lubricated without actual contact by the applicator but merely by proper coaction therewith.

The advantages and simplicity in construction of the lubricators herein disclosed will be apparent to those skilled in the art, as, for instance, the means by which the compound movement of the turn-push and push-turn types is obtained with a limitation of the extent of the first directional part of the lubricating movement, and the means by which the cocking and therefore binding of the plungers of all three embodiments is prevented by providing concentric surfaces movable with the manual operating means on the exterior and interior surfaces of the supporting means. It will be understood also that many other modifications may be made, as for instance the following: the turn-push type may also be mounted in the interrupter cap instead of in the side wall of the interrupter housing as shown, and the push-turn

and the turn types may be mounted in the side wall instead of in the cap as shown; and the return movement of the lubricant applicator to normal or inoperative position in the three types herein disclosed need not be in the reverse direction or sequence to the movement to apply the lubricant. It will therefore be understood that the terms of the appended claims should be given their broadest interpretation and scope.

10. Having thus described the invention, what is claimed is:

1. The combination with an ignition generator having an interrupter housing, a shaft in said housing, and interrupter mechanism operable by the shaft; of a manual lubricator which is fastened to the housing and which includes a lubricant applicator, manual operating means which is constructed and arranged to move the applicator in a compound movement from normal position out of coaction with the interrupter mechanism to a lubricating position in coaction therewith and which has a stop intermediate said positions to limit the extent of the first directional part of the compound movement, and means automatically effective upon release of the operating means at said lubricating position to return the same and the applicator to said normal position.

2. The combination with an ignition generator having an interrupter housing including a side wall and a cap removably fastened to the side wall over the outer open end thereof, a shaft terminating within the interrupter housing, and interrupter mechanism operable by the shaft; of a manual lubricator which is fastened solely to the cap so as to be removable therewith and which includes a lubricant applicator extending within the housing, manual operating means which extends outside the cap and which is constructed and arranged to move the applicator in a compound movement from normal position out of coaction with the interrupter mechanism to a lubricating position in coaction therewith and has a stop intermediate said positions to limit the extent of the first directional part of the compound movement, and automatic means effective upon release of the operating means to return the same and the applicator to a position in which the applicator is out of coaction with the interrupter mechanism.

3. The combination with an ignition generator having an interrupter housing, a shaft in said housing, and interrupter mechanism operable by the shaft; of a manual lubricator which is fastened to the housing and which includes a lubricant applicator, manual operating means which is constructed and arranged by a compound movement thereof including a turning operation for a part of the movement and a longitudinal operation for another part of the movement to bring the applicator from its normal position out of coaction with the interrupter mechanism to a lubricating position in coaction therewith and which has a stop limiting the extent of the first of said directional operations, and means automatically effective upon release of the operating means at said lubricating position to return the same and the applicator to said normal position.

4. The combination with an ignition generator having an interrupter housing, a shaft in said housing, and interrupter mechanism operable by the shaft; of a manual lubricator which is fastened to the housing and which includes a lubricant applicator, manual operating means

which is constructed and arranged by a compound movement thereof including a turning operation for the first part of the movement and a longitudinal operation for the second part of the movement to bring the applicator from its normal position out of coaction with the interrupter mechanism to a lubricating position in coaction therewith and which has a stop limiting the angular extent of said turning operation, and means automatically effective upon release of the operating means at said lubricating position to return the same and the applicator to said normal position.

5. The combination with an ignition generator having an interrupter housing, a shaft in said housing, and interrupter mechanism operable by the shaft; of a manual lubricator which is fastened to the housing and which includes a lubricant applicator, manual operating means which is constructed and arranged by a compound movement thereof including a longitudinal operation for the first part of the movement and a turning operation for the second part of the movement to bring the applicator from its normal position out of coaction with the interrupter mechanism to a lubricating position in coaction therewith and which has a stop limiting the longitudinal extent of said longitudinal operation, and means automatically effective upon release of the operating means at said lubricating position to return the same and the applicator to said normal position.

6. The combination with an ignition generator having an interrupter housing, a shaft in the housing, and interrupter mechanism operable by the shaft; of a manual lubricator which is fastened to the housing and which includes a lubricant applicator, supporting means fast with the housing for supporting the lubricator thereon, manual operating means connected to the applicator for moving it from normal position out of coaction with the interrupter mechanism into lubricating position in coaction therewith, and means automatically effective upon release of the operating means at said lubricating position to return the same and the applicator to said normal position, said supporting and operating means having cooperative guiding mechanism with an intermediate stop which guides the applicator in a compound movement between said normal and lubricating positions.

7. The combination with an ignition generator having an interrupter housing, a shaft in the housing, and interrupter mechanism operable by the shaft; of a manual lubricator having a lubricant applicator, a plunger fast with the applicator; supporting means which is fast with the housing for supporting the lubricator therefrom, and which includes a compound guiding surface, a shaft extension movable on an interior surface of the supporting means, a pin connecting the plunger and shaft extension and cooperating with the guiding surface to guide the plunger in a compound movement between extreme positions, a manually operative hollow cylindrical handle fastened to the shaft extension and movable on an exterior surface of the supporting means, and a coil spring which surrounds the plunger and has its ends fastened to the supporting means and the shaft extension respectively.

8. The combination with an ignition generator having an interrupter housing, a shaft in the

housing, and interrupter mechanism operable by the shaft; of a manual lubricator having a lubricant applicator, a plunger fast with the applicator, a supporting member which is fast with the housing for supporting the lubricator therefrom and which has a hollow cylindrical extension and a compound guiding surface, a shaft extension, a pin connecting the plunger and shaft extension and cooperating with the guiding surface to guide the plunger in a compound movement between extreme positions, a manually operable handle fastened to the shaft extension for moving the applicator in a compound movement, as determined by the pin and guiding surface, into coaction with the interrupter mechanism to lubricate the same, and a spring which is effective upon release of the handle to return the applicator to normal position out of coaction with the interrupter mechanism, said shaft extension and said handle being slidable on the interior and exterior surfaces of the cylindrical extension.

9. The combination with an ignition generator having an interrupter housing, a shaft in the housing, and interrupter mechanism operable by the shaft; of a manual lubricator having a lubricant applicator, a plunger fast with the applicator, supporting means which supports the lubricator from the housing and which has a bushing with a compound guiding surface and also a nut with a cylindrical extension screwed on the bushing, a shaft extension, a pin which fastens the plunger and shaft extension and which extends into cooperation with the guiding surface to guide the plunger in a compound movement between extreme positions, a manually operable handle fastened to the shaft extension for moving the applicator in a guided movement, as determined by the pin and guiding surface, into coaction with the interrupter mechanism to lubricate the same, and a spring which is effective upon release of the handle to return the applicator to normal position out of coaction with the interrupter mechanism, said shaft extension being movable on the interior surface of the bushing and the interior surface of the handle being movable on an exterior surface of the cylindrical extension of the nut.

10. In a manual lubricator adapted to be fastened to the interrupter housing of an ignition generator having interrupter mechanism operable by a shaft in the housing, a lubricant applicator, a plunger fast with the applicator, supporting means which is adapted to be fastened to the interrupter housing to support the lubricator therefrom and which includes a hollow cylindrical extension with a compound guiding surface to guide the plunger in a compound movement between extreme positions, a shaft extension slidable on an interior surface of the cylindrical extension, a pin connecting the plunger and shaft extension and cooperative with the guiding surface, a hollow cylindrical handle fastened to the shaft extension and slidable on an exterior surface of the supporting means, and a spring which is effective upon release of the handle to return the applicator from its lubricating position in coaction with the interrupter mechanism to its normal position out of such coaction.
